METHOD OF MAKING FLAT RIB WELT SHOES

Ralph E. Pearsall, Gloucester, and Lawrence A. Sever, Rockport, Mass., assignors to United Shoe Machinery Corporation, Flemington, N. J., a corporation of New Jersey

Application December 6, 1955, Serial No. 551,367

3 Claims. (Cl. 12—142)

This invention relates to the manufacture of welt shoes, and more particularly of welt shoes of the flat lasted type.

In the construction of the standard Goodyear welt shoe the upper, with the exception of the heel end portion which is lasted and secured directly to the heel seat portion of the insole, is lasted to an upstanding rib either formed by cementing together the upturned lips of the channels cut in the insole, or provided by a ribbed strip attached to the insole. The toe portion of the upper, including the lining and the box toe, is wiped inwardly over the last and against the insole rib by toe embracing wipers and secured in lasted position by temporary binder wire anchored with upstanding tacks at opposite sides of the toe end of the shoe. The sides of the upper are tensioned over the margin of the insole and secured in lasted position by staples driven through the upper materials and the insole rib and clinched on the inner face of the rib. After the lasting, a welt is sewed to the upper and the insole rib; this operation being known as the inseaming. This is followed by the inseam trimming, which consists of trimming off the surplus materials of the insole rib, the upper materials and the welt close to the row of staples by which the upper is secured to the rib at the sides of the shoe. Bottom filler is then applied, and the usual bottoming operations are performed to complete the construction of the shoe.

While this method has long been acknowledged to be the most suitable for the construction of high quality shoes, it is admittedly expensive, by reason of the many operations involved.

It is therefore one object of the present invention to provide a method of manufacturing welt shoes having all the desirable characteristics of the Goodyear welt shoe, together with the advantages of lightness and flexibility, but which may be manufactured at substantially less cost.

In its broad method aspect the invention comprises providing an insole having a flat lasting rib or lip, lasting the toe end of an upper to this rib and securing it in lasted position, preferably by means of cement, lasting the heel end to the heel seat portion of the insole, then lasting the sides of the upper to the flat rib and, simultaneously with that operation, attaching a welt around the periphery of the shoe, from the heel breast line at one side to the heel breast line at the opposite side, by a single row of staples inserted in a plane substantially normal to the insole, the staples passing through the welt, the upper, and the insole rib and being clinched to the inner face of the rib, and thereafter bonding the lasting rib, together with the lasted margin of the upper and the welt, to the insole body, the shoe being finished in the usual manner.

It will be appreciated that by lasting the upper to an insole rib that is flat from the beginning and which remains substantially flat throughout the lasting and weltting operations, the upper and welt, at the end of these operations, are secured in practically the positions which they will occupy in the finished shoe, with little or no

2

additional strain imposed on the upper in securing it in its lasted position on the insole.

Flat lasting has been recognized as desirable in the making of shoes because of the greater degree of flexibility possessed by shoes thus made and also because it permits the use of prefitted uppers, which represent substantial savings in upper materials. However, heretofore flat lasting has been restricted mainly to the manufacture of non-welt or imitation welt shoes with cement-attached soles. Where flat lasting is practiced in the manufacture of welt shoes, the upper is first lasted and secured to the insole by fastening means, such as staples, and the welt thereafter secured to the overlasted upper and the insole by separate fastening means, such as stitches or staples. Usually, the staples are driven through the welt; the upper, and the insole and clinched on the inner surface of the insole or, in some instances, driven part way through the insole and clinched within the thickness of the insole. Where the fastenings are driven through the insole, it is necessary to use a last having a metal plate on its bottom for the clinching of the staple legs, and a sock lining is required to cover the fastenings and protect the wearer's foot. Also, where the welt is secured to the upper and insole by stitching, it is necessary to remove the last from the shoe and to relast the shoe for the later operations.

According to other methods practiced heretofore, the upper is lasted to an upstanding rib provided on the insole and, after attachment of a welt to the lasted upper and rib, the rib, together with the upper and welt, are turned or bent inwardly to bring them into parallel relation to the surface of the insole and secured to the insole either by cement or other means. This method is undesirable because in the operation of bending the materials into a flat position the upper, which has already been subjected to all the strains it is capable of withstanding in the lasting operation, is subjected to further stretching strains which can result in impairing the securement of the upper and rib to the insole or weakening the inseam, with resulting "grinning" at the crease between the upper and the welt.

The method according to the present invention offers the shoe manufacturer the possibility of making welt shoes at substantial savings in manufacturing cost by combining into a single operation the separate operations of side lasting and inseaming and by eliminating the inseam trimming operation. The method provided by the invention affords further savings in cost of production by making it possible to use inexpensive insole stock, no channeling being necessary, and by eliminating the need of a sock lining in the interior of the shoe, since no fastenings penetrate the insole.

The invention will now be more fully described, with reference to the accompanying drawings, and particularly pointed out in the appended claims.

In the drawings:

Fig. 1 is a perspective view of one form of insole to which an upper may be lasted in the practice of the method according to the invention;

Fig. 2 is a perspective view of a modified insole provided with a bevel along its margin;

Fig. 3 is a perspective view of a shoe made in accordance with the method of the present invention;

Fig. 4 is a sectional view of the forepart of the shoe illustrated in Fig. 3 with an outsole attached thereto;

Fig. 5 is a perspective view of a modified form of the insole shown in Fig. 1, the illustrated insole being provided with a different type of lasting rib;

Fig. 6 is a perspective view of another modification, this view showing a laminated insole from which a band has been cut to provide a lasting rib;

Fig. 7 is a similar view of still another modification of the insole illustrated in Fig. 1;

Fig. 8 is a perspective view of the head of a staple side lasting and welt attaching machine which may be used in the practice of the method according to the invention;

Fig. 9 is a detail plan view, partly in section, showing the principal lasting and stapling instrumentalities of the machine; and

Fig. 10 is a sectional view taken along the line X—X of Fig. 9.

In constructing a welt shoe in accordance with the method provided by the present invention an upper 20 is assembled and pulled over a flat rib or lip, such as the rib 22 shown in Fig. 1, and temporarily secured by tacks to an insole 24 mounted on a last 26. The term "upper" is used herein generically to designate all upper materials, such as a lining, box toe, and other components. The rib 22 of the insole 24 shown in Figs. 1 and 2 is a composite rib comprising an outer strip 32 of felted fibrous material coated on its inner face with cement, preferably pressure-responsive cement, and an inner strip 34 of a material such as canvas, wider than the strip 32 and coated on both sides with a similar cement, the strip 34 being folded upon itself lengthwise and the strip 32 adhering to the upper fold of the strip 34, the lower fold of which is bonded to the margin of the insole 24 which is coated with cement, as shown at 36. As may be seen in Fig. 1, the outer strip 32 extends somewhat beyond the upper fold of the fabric strip 34 inwardly of the insole, in order that the composite rib 22 may adhere lightly to the body portion of the insole. This is advantageous in that it prevents the cement sprayed in preparation for the toe lasting operation from flowing under the rib, and also helps maintain the rib flat against the insole so that it will not interfere with the operation of the grippers of the side lasting machine, while permitting the anvil of the stapling mechanism of the machine to get under the rib during the stapling operation, as will appear hereinafter.

Preferably, though not necessarily, the margin of the insole 24 may be beveled or skived to a feather edge, as shown at 38 (Fig. 2), in order to insure greater flexibility of the insole due to the thin feather edge, and to insure at the same time that the over-lasting margin of the upper and the welt will lie in a lower plane relatively to the insole surface, thus reducing the inseam bulk and the amount of bottom filler required.

In place of the rib 22 shown in Figs. 1 and 2, the insole may be provided with a rib such as that illustrated in Fig. 5. This rib consists of an upper strip 40 of a material similar to that of the strip 32, and a lower strip 42 of a material such as canvas, the two strips being first secured together along their outer edges by stitching 44 and attached to the insole by cement only.

Other types of insoles which may be used in practicing the method according to the invention are illustrated in Figs. 6 and 7. The insole shown in Fig. 6 is a laminated insole comprising an upper or outer layer 48 and a lower or inner layer 50 of any suitable insole material, the upper layer having a cut formed through its thickness at a distance from the margin of that layer, to provide a free rand or lip 46 and an "island" portion bonded to the lower layer 50.

The insole shown in Fig. 7 is substantially similar to that previously described and comprises a free rand or lip 52 obtained by forming a cut 54 in an upper or outer layer 56 of any suitable material, the central portion of which forms an "island" which is cemented to a lower or inner layer 58. The rand or lip 52 is connected to the "island" portion of the upper layer 56 by spaced frangible connections 60, which aid in maintaining the lip flat against the insole during the lasting operation while permitting the anvil to engage under the lip during the

stapling operation, the frangible connections being severed by the anvil as the stapling proceeds around the shoe.

The upper having been pulled over as explained above, the heel and toe end portions of the upper are lasted, these operations being conveniently performed in bed lasting machines in the conventional manner, the toe end portion being secured in lasted position, preferably by cement, to the rib or lip of the insole, while the heel end portion is secured by tacks to the heel seat portion of the insole, according to the usual practice in the manufacture of welt shoes.

The shoe is next presented to a staple side lasting and welt attaching machine in which successive portions of the sides of the upper (including the lining, if there is one) are tensioned over the lip or rib and, while each successive portion of the upper is held under tension, a welt 28, fed in timed relation to the operation of the tensioning means, is applied to the upper, and at the same time a staple 30 is inserted vertically through the welt, the upper, and the insole lip or rib and clinched to the inner face of the lip or rib, thereby securing the upper in lasted relation to the insole and attaching the welt in one operation.

A machine suitable for performing the side lasting and welt attaching operations, as above described, is illustrated in Figs. 8, 9, and 10, the principal instrumentalities of this machine comprising a pair of upper tensioning gripper jaws 62, 62, a welt guide 64, a staple nozzle 66, a staple driver 68, and an anvil 70 arranged to engage under the insole lip or rib to support the lip, the upper and the welt during the insertion of a staple which is driven into a groove 72 in the welt and is clinched to the inner face of the insole lip.

The lasting operation commences at the heel breast line at one side of the shoe and proceeds progressively until the tip line of the already-lasting toe portion of the upper is reached, whereupon the gripper jaws are thrown out of operation until the tip line on the opposite side of the shoe is reached, at which point the gripper jaws resume the lasting operation which continues to the heel breast line at that side of the shoe. The insertion of staples, however, for securing the welt to the upper, continues without interruption from breast line to breast line, the shoe being fed progressively (by mechanism not herein shown) past the anvil 70 located under the insole lip.

After the staple lasting of the sides of the upper and attachment of the welt, the insole lip or rib, regardless of which of the several types of insole previously described is used, is coated with a suitable cement, and the shoe bottom is subjected to pressure to cause the lip or rib to adhere firmly to the shoe bottom, that is to the portion of the rib which is secured to the insole, if the rib is of the type of those shown in Figs. 1 to 5, or directly to the margin of the insole, if the lip is in the form of a rand cut from the insole, as in the constructions illustrated in Figs. 6 and 7. The shoe is now ready for the bottoming operations, no inseam trimming being necessary, as in the usual welt construction, by reason of the lasting of the upper and the attachment of the welt to a flat rib. Bottom filler F may now be applied in the forepart of the shoe, the amount of filler required being substantially less than that required when the upper is lasted and the welt sewn to an upstanding rib. The shoe 65 may be completed by attaching an outsole S either by stitching or by cement, in the usual manner known to those skilled in the art.

It will be readily appreciated from the foregoing description that the method provided by the present invention offers many advantages in the manufacture of welt shoes. From an economic point of view, it affords substantial savings in manufacturing costs by eliminating some of the operations necessary in the making of welt shoes by present conventional methods. The use of a flat lasting rib of any one of the types herein disclosed

is compatible with other shoemaking processes which utilize flat lasting, as, for example, the cemented shoe process, so that factories equipped with flat lasting machines can readily produce welted shoes with either extension or close edge soles. From a quality standpoint, the method provided by the present invention makes it possible to produce shoes possessing the highly desirable characteristics of lightness and flexibility, without sacrificing any of the acknowledged advantages of the true Goodyear welt shoe, such as the tight joint between the upper and the shoe bottom and the smooth interior of the shoe, exempt from any seams or metallic fastenings. It will be noted also that the shoe remains on the last throughout the entire period of its manufacture, thereby contributing toward imparting to the shoe the desired shape.

Having thus described our invention, what we claim as new and desire to secure by Letters Patent of the United States is:

1. In the art of making welt shoes, the steps which comprise providing upon a last an insole having a flat rib attached thereto and extending inwardly from its margin in a plane substantially parallel to the outer surface of the insole, providing an upper having a lasting margin, pulling the upper over the last, lasting the heel end of the upper to the heel seat portion of the insole lasting the toe end of the upper to the inwardly extending flat rib, and then completing the lasting of the shoe along the opposite sides progressively by tensioning the upper heightwise of the shoe and drawing its margin inwardly over the rib in parallel relation to the insole in different locations successively and simultaneously attaching a welt around the periphery of the shoe from the heel breast line at one side to the heel breast line at the opposite side of the shoe, without any distortion of the welt heightwise of the shoe, by a single row of staples inserted through the welt, the upper and the rib in a direction substantially perpendicular to the insole.

2. In the art of making welt shoes, the steps which comprise providing upon a last an insole having a flat rib attached thereto and extending inwardly from its margin in a plane substantially parallel to the outer surface of the insole, providing an upper having a lasting margin, pulling the upper over the last, lasting the heel end of the upper to the heel seat portion of the insole, lasting the toe end of the upper to the inwardly extending flat rib, and then completing the lasting of the shoe along the opposite sides progressively by tensioning the upper heightwise of the shoe and drawing its margin inwardly over the rib in parallel relation to the insole in different locations successively and simultaneously laying a welt against the overlasted, inwardly extending margin of the upper progressively around the periphery of the shoe from the heel breast line at one side to the heel breast line

5 at the opposite side of the shoe and inserting at each successive portion of the shoe upper while held under tension a staple through the welt, the upper and the rib in a direction substantially perpendicular to the plane of the insole, to secure the welt and the upper to said rib in the position which they will occupy in the finished shoe.

3. In the art of making welt shoes, the steps which comprise: providing upon a last an insole having a pre-fabricated flat rib attached thereto and extending inwardly from its margin in a plane substantially parallel to the outer surface of the insole, said rib comprising a two-ply portion formed by adhesively bonding a strip of fibrous material and a strip of fabric wider than said first-named strip, said fabric strip being folded upon itself and having the portion thereof which extends beyond said strip of fibrous material adhesively secured to the insole margin; providing an upper having a lasting margin; pulling the upper over the last; lasting the heel end of the upper to the heel seat portion of the insole; lasting the toe end of the upper to the inwardly extending two-ply rib portion; completing the lasting of the shoe along the opposite sides progressively by tensioning the upper heightwise of the shoe and drawing its margin inwardly over said two-ply rib portion in parallel relation to the insole in different locations successively and simultaneously laying a welt against the overlasted inwardly extending margin of the upper progressively around the periphery of the shoe from the heel breast line at one side to the heel breast line at the opposite side of the shoe and inserting at each successive portion of the shoe upper held under tension a staple through the welt, the upper and the rib in a direction substantially perpendicular to the plane of the insole to secure the welt and the upper to said two-ply rib portion in the position which they will occupy in the finished shoe; adhesively bonding said two-ply rib portion to the portion of the fabric strip which is secured to the insole to secure the upper in flat lasted condition; and completing the shoe by attaching an outsole to the welt.
